UNITED STATES PATENT OFFICE.

FRANCIS W. KRAMER, OF PHILADELPHIA, PENNSYLVANIA.

TOY-CAR COUPLING.

1,186,994.

Specification of Letters Patent. Patented June 13, 1916.

Application filed March 21, 1916. Serial No. 85,557.

To all whom it may concern:

Be it known that I, FRANCIS W. KRAMER, a citizen of the United States, residing in the city and county of Philadelphia, State 5 of Pennsylvania, have invented a new and useful Toy-Car Coupling, of which the following is a specification.

My invention consists of couplings adapted for toy cars, formed of few members of inexpensive and durable construction, the same being easily operated in both coupling and uncoupling, as will be herein-after more fully described.

The invention is satisfactorily illustrated 15 in the accompanying drawing, but the important instrumentalities thereof may be varied, as long as they are included in the scope of the claims.

Figure 1 represents a side elevation of a 20 car coupling embodying my invention. Figs. 2 and 3 represent bottom plan views thereof, respectively, in coupled and uncoupled condition. Fig. 4 represents a perspective view of one of the couplings detached. 25 Fig. 5 represents a vertical section of a portion of the coupling, and a portion of a car at the coupling end of the latter.

Similar numerals of reference indicate 30 corresponding parts in the figures.

Referring to the drawings, 1 designates the draw head of the coupling, the same consisting of the horizontally-extending bar 2, the lips 3 depending angularly from the opposite sides thereof, and the elbow lever 35 4 which is connected by the pivot 5 with the underside of the floor of the body of the car. The limb 6 of said elbow lever extends rearwardly from the bar 2, and the limb 7 thereof extends to the side of the car, 40 whereby it is provided with the finger piece 8, whereby said lever, and consequently the draw head may be manipulated for coupling and uncoupling opposite cars.

Extending forwardly from one of the lips 45 3 is the coupling head 9 in the form of a nose composed of the slope 10, and shoulder 11, it being noticed that in the present instance, said nose, lip, bar and elbow lever are formed integral of metal.

The other lip 3 has riveted or otherwise 50 connected with it the spring 12, which occupies a position on the draw head in front thereof, opposite to the coupling head, said spring in the present case being of V-shape, 55 one limb of each of which is secured to the adjacent lip, and the other limb is free so as

to yield, as will be hereinafter again referred to.

The limb 6 is adapted to play between the floor of the body of the car, and the connecting bar 13 of the steps 14 of the car, said bar thus assisting to support said limb, and the appurtenances of the coupling thereof.

Each car is equipped with the coupling, 65 and when the cars approach the slopes or sloping sides 10 of the heads 9, ride on each other, the elbow lever turning sufficiently to allow the same, the free limbs of the springs 12 yielding, and being compressed as said 70 heads bear laterally on the same.

When the shoulders 12 clear each other, the heads spring toward each other, so that said shoulders lap each other, and so cause the coupling of the opposite heads, the 75 springs 12 then pressing laterally on said heads and holding them connected or coupled, in which position they will remain in the running of the cars.

In order to uncouple the cars, the levers 80 4 are moved by the finger pieces 8 in the direction toward the coupled ends of the cars as shown by the dotted lines and arrows in Fig. 3. By this provision the draw heads are separated laterally and the springs yield, 85 as shown also in said Fig. 3, said heads thus being disconnected and the cars uncoupled.

Having thus described my invention what I claim as new and desire to secure by Letters Patent, is:—

1. A coupling for a toy car consisting of a draw head formed of a bar, lips depending from the sides thereof, a coupling head projecting forwardly from one of said lips, and a resilient member projecting forwardly from the other lip, said resilient member and head being comparatively opposite, both on the same draw head.

2. A coupling for a toy car consisting of a draw head formed of a bar, lips depending from the sides thereof, a coupling head projecting forwardly from one of said lips, a resilient member projecting forwardly from the other lip, said resilient member and head being comparatively opposite, both on the same draw head, and a lever adapted to carry said draw head and form means for operating the latter for uncoupling purposes.

3. In a coupling for a toy car, a draw head composed of a bar, angular lips on said bar, a coupling head continuous on one of

said lips, and a resilient member, said head, lips and bar being of integral construction, the other lip being adapted to support said resilient member opposite to said coupling head.

4. In a coupling for a toy car, a draw head composed of a bar, angular lips on said bar, a coupling head on one of said lips, a resilient member, and a lever carrying said bar adapted to be pivotally mounted on the car, said lever, head, lips and bar being of integral construction, the other lip being

adapted to support said resilient member thereon opposite to said coupling head.

5. In a coupling for a toy car, a coupling head, a lever adapted to carry the latter and being pivotally mounted on the car, and a cross bar on the car below the floor thereof on which a limb of said lever is adapted to play.

FRANCIS W. KRAMER.
